UNITED STATES PATENT OFFICE

EDWARD F. PINK, OF CAMBRIDGE, MARYLAND

WOVEN WIRE BELT

Application filed September 5, 1930. Serial No. 479,996.

This invention relates to improvements in woven wire belts or aprons formed of interwoven spiral wire coils, the general object of the invention being to so construct and arrange the parts as to balance the strain set up during the operation of the belt and thus prevent belt distortion.

The present invention is an improvement over that forming the subject matter of a patent granted to me on April 2, 1929, No. 1,707,567.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Fig. 1 is a face view of portion of the improved belt or apron;

Fig. 2 is a similar view, but showing the two longitudinal sections of the belt separated; and

Fig. 3 is a diagrammatic view showing how the various sections of the belt act to prevent distortion.

As shown in these views, the belt or apron is formed of the two longitudinal sections C and D. Each section is composed of a plurality of sections, alternate sections of the longitudinal section C being indicated by the letter A and the remaining sections by the letter B, while the alternate sections of the longitudinal section D are indicated by the letter A' and the remaining sections by the letter B'. Each section of each longitudinal section is composed of a plurality of helical wires 1 which extend transversely of the belt, the convolutions of each member or wire being interlocked or interwoven with the convolutions of the adjacent wires. The outer and inner portions of these convolutions form diagonal ribs on the outer and inner side of the belt, the ribs at the inner side or surface bearing on the supporting drums or pulleys, while the ribs on the outer surface support

the articles or material being conveyed by the belt. Each pair of wires is connected together at their ends in any suitable manner, such as by welding or the like, as shown at 2. The helical members of each section of each of the longitudinal sections are reversely arranged to those of the adjacent sections of the longitudinal section so that the outer and inner ribs of one section extend in an opposite direction from the outer and inner ribs of the adjacent sections. In other words, the helical wires of the section A or A' are reversely arranged to the helical wires of the sections B or B' and the two sections C and D are so placed that the helical members of each section of one of the longitudinal sections are reversely arranged to the opposing sections of the other longitudinal section.

The drawings show the sections of the longitudinal sections connected together by the cross rods 3, each rod connecting together two of the sections of one longitudinal section and the opposing sections of the other longitudinal section. The ends of the rods are suitably connected with the edges of the belt, as shown at 4. The sections of each longitudinal section, however, may be connected together in any other suitable manner.

Figure 1 shows the wires of the longitudinal sections connected together by welding, as shown at 5, but these wires can be connected together in any other suitable manner or they may be separated or not connected together, as shown at 6 in Figure 2.

While the drawings show a belt constructed of two longitudinal sections, it will, of course, be understood that the belt may be composed of a plurality of longitudinal sections, if desired.

Thus it will be seen that I have provided a belt composed of a pair of longitudinal sections, with each section composed of small sections suitably connected together, with the wires of alternate small sections being reversely arranged to the wires of the other sections and the wires of each small section being reversely arranged to the wires of the opposing small section of the other longitudinal section of the belt.

In order that a spiral wire belt may be prevented from displacing itself by crawling or creeping edgewise upon the driving drums, pulleys and other supports, it is essential that right and left direction spirals be used. As such a belt in its operation comes in frictional contact with its supports, the sections are continually endeavoring to move in opposite directions so that there are two forces set up which are continually opposing one another. Such forces tend to separate the sections and where the separation is prevented, as by fastening the adjacent ends of the sections together, as shown in my before mentioned patent, the coils of the spirals tend to spread so that the width of the belt is increased. In order to prevent the sections from spreading or the coils spreading and increasing the width of the belt, I construct the belt as above described, which arrangement sets up four opposing forces and two like forces, instead of the usual two opposing forces. This is illustrated in Figure 3, where the tendency of section A to move in the direction of the arrow b' is opposed by the tendency of the section A' to move in the direction of the arrow b^2 and the tendency of the section B to move in the direction of the arrow b^3 is opposed by the tendency of the section B' to move in the direction of the arrow b^4 . Thus the force b' opposes b^2 in an outward transversal direction, b^3 opposing b^4 in an inward transversal direction, b^3 opposing b' in a lateral direction and b^4 opposing b^2 in an opposite lateral direction, b' complementing b^4 and b^2 complementing b^3 in direction. Thus the two longitudinal sections C and D are prevented from continually endeavoring to separate at their point of connection indicated by the line c and there is no abnormal strain upon the points of connection. Also, the spirals of the two longitudinal sections are prevented from lengthening, which would increase the width of the belt. It will be seen that by thus crossing the forces or by reason of having created a new pair of forces, I have counteracted the existing or original pair of forces so that they are actually shattered or broken up in a manner that prevents any abnormal strain of one section against another and, therefore, preventing belt distortion.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A wire belt composed of a number of longitudinally extending sections, each section being formed of small sections connected together, each section being composed of heli-

cal members extending crosswise of the section and interlocking, the members of alternate small sections of each longitudinal section being reversely arranged to the members of the other small sections of said longitudinal section, and the helical members of each small section of one longitudinal section being reversely arranged to the opposing small section of the other longitudinal section.

2. A wire belt composed of a number of longitudinally extending sections, each section being formed of small sections connected together, each section being composed of helical members extending crosswise of the section and interlocking, the members of alternate small sections of each longitudinal section being reversely arranged to the members of the other small sections of said longitudinal section and the helical members of each small section of one longitudinal section being reversely arranged to the opposing small section of the other longitudinal section, and means for rigidly and permanently uniting the adjacent edges of the longitudinal sections.

3. A wire belt composed of a number of longitudinally extending sections, each section being formed of small sections connected together, each section being composed of helical members extending crosswise of the section and interlocking, the members of alternate small sections of each longitudinal section being reversely arranged to the members of the other small sections of said longitudinal section and the helical members of each small section of one longitudinal section being reversely arranged to the opposing small section of the other longitudinal section, and means for rigidly and permanently uniting the adjacent edges of the longitudinal sections, and rods connecting the small sections of the longitudinal sections together.

4. A wire belt composed of a number of longitudinally extending sections, each section being formed of small sections connected together, each section being formed of helical members extending crosswise of the section and interlocking, the members of alternate small sections of each longitudinal section being reversely arranged to the members of the other small sections of said longitudinal section and the helical members of each small section of one longitudinal section being reversely arranged to the opposing small section of the other longitudinal section, and rods connecting the small sections of the longitudinal sections together, each rod uniting a pair of small sections of the longitudinal sections.

5. A wire belt composed of a number of longitudinally extending sections, each section being formed of small sections, each section being composed of helical members extending crosswise of the section and interlocking, the members of alternate small sections

- of each longitudinal section being reversely arranged to the members of the other small sections of said longitudinal section and the helical members of each small section of one longitudinal section being reversely arranged to the opposing small section of the other longitudinal section, and means connecting the small sections of the longitudinal sections together.
6. A wire belt composed of a number of longitudinally extending sections, each section being formed of small sections, each section being composed of helical members extending crosswise of the section and interlocking, the members of alternate small sections of each longitudinal section being reversely arranged to the members of the other small section of said longitudinal section and the helical members of each small section of one longitudinal section being reversely arranged to the opposing small section of the other longitudinal section, means for rigidly and permanently uniting the adjacent edges of the longitudinal sections, and means connecting the small sections of the longitudinal sections together.
7. A wire belt composed of a number of longitudinally extending sections, each section formed of small sections, each section being composed of helical members extending crosswise of the section and interlocking, the members of alternate small sections of each longitudinal section being reversely arranged to the members of the other small sections of said longitudinal section and the helical members of each small section of one longitudinal section being reversely arranged to the opposing small section of the other longitudinal section, and rods hinging the small sections of the longitudinal sections together.

In testimony whereof I affix my signature.
EDWARD F. PINK.
